UNITED STATES PATENT OFFICE

BERNARD YOUNG, OF SAN PEDRO, CALIFORNIA

PISTON RING

Application filed September 4, 1929. Serial No. 390,248.

This invention relates to a piston ring or packing which is used upon the pistons in internal combustion engines, pumps, compressors or the like.

5 An object of my invention is to regulate the pressure of the ring against the wall of the cylinder.

Another object is to provide a ring which is made up of two or more components parts, 10 a wearing ring or rings, and a control ring which holds the wearing ring in check.

Other objects, advantages and features of invention may appear from the accompanying drawing, the subjoined detailed description and the appended claims.

In the drawing

Figure 1 is a fragmentary longitudinal sectional view of a cylinder with a piston therein, the piston being broken away to 20 show interior construction.

Figure 2 is a fragmentary plan view of one of the rings with the links in position therein.

Figure 3 is a side elevation of one of the 25 links.

Figure 4 is a fragmentary plan view of one of the rings the view being taken at the split in the ring.

Figure 5 is a fragmentary side elevation 30 of a ring, the view being taken at the slit in the ring.

Figure 6 is a transverse sectional view of a slightly modified form of ring.

Referring more particularly to the drawing, my piston ring 1 comprises a wearing ring 2 and a control ring 3. As here shown, 35 the wearing ring is on top, and the control ring below. The wearing ring which always is in contact with the walls of the cylinder 4, and it is the purpose of my invention to so control the pressure or wearing ring against the wall of the cylinder so that no excessive wear will be created. That is 40 the cylinder with a comparatively equal pressure irrespective of the position of the piston in the cylinder.

The piston 5 is provided with the usual 50 annular ring groove 6 in which the ring 1 is positioned. A duct 7 extends from ad-

jacent the upper end of the piston into the groove 6 so that the compression pressure in the cylinder is lead back of the rings for the purpose of forcing the rings outwardly so that they will bear against the wall of the cylinder and then seal the space between the piston and the cylinder.

The inner area of the rings 2-3 may be different so that one ring or the other is forced outwardly by a greater force due to the pressure in the groove 6. The theory of this arrangement is described in my co-pending application, serial number 361,299 for piston rings.

Without a control ring, the wearing ring 2 would be forced against the wall of the cylinder so tightly that there would be excessive wear, but I equalize or control this outward force against the wearing ring by means of the control ring 3. That is, as 70 the wearing ring 2 is forced outwardly, the control ring 3 will be forced inwardly or contacted and conversely as the control ring 3 is expanded or moved outwardly, the wearing ring 2 will be contracted or moved inwardly.

I accomplish this adjustment between the two rings in the following manner: The ring 2 is split as at 8 and the ring 3 is split as at 9. The openings or splits 8-9 are 80 positioned one above the other as shown in Figure 1, and leakage is prevented past these splits by a sealing strip 10 which extends under the bottom ring and upwardly on the inside of both of the rings.

The rings 2, 3 are coupled together at the split in each by means of links 11-12. The ring 2 is provided with slots or recesses 13-14, one such slot or recess being adjacent the side of the split 8. The slots 13-14 are formed in the bottom of the ring 2 and the ring 3 which also is formed with a pair of slots identical in construction and arrangement to the slots in ring 2. The only difference is that in the ring 3 the slots are 95 in the top surface of the ring. These slots are shown at 15-15.

The rings 2-3 are also reduced in thickness between the slots 13-14 as shown at 17 so that the links 11-12 will fit between the 100

rings. The link 11 is provided with an upwardly extending lug 18 at the one end thereof, and a downwardly extending lug 19 on the opposite end thereof. The lug 18 fits in the slot 16 in the ring 3, and the lug 19 fits in the slot 13 of the ring 2. The link 12 is provided with an upwardly extending lug 20 at one end thereof, and a downwardly extending lug 21 at the other end thereof. 5 Similarly the lug 20 fits in the slot 14 of the ring 2 and the lug 21 fits in the slot 15 of the ring 3. That is, one end of each of the links 11—12 is secured to the upper ring on one side of the slot therein, and the other end is secured to the lower ring on the other side of the slot. By this arrangement as the lower ring expands or contracts, the upper wearing ring will move in the opposite direction, thus the wearing ring is 10 effectively controlled and prevented from pressing with too great a pressure against the wall of the cylinder.

In Figure 6 I have shown a slightly modified form of ring which is shrouded, that is, the upper wearing ring 22 is provided with a depending annular skirt or shroud 23 which covers the control ring 24. The purpose of this arrangement is to prevent any pressure from being exerted on the outer 25 face of the control ring by reason of leakage past the wearing ring. With this arrangement the control ring is always free to be acted upon by the pressure in the ring groove so that the wearing ring is effectively 30 controlled at all times. The connecting links 25, 26 are the same as those previously described, and need not be described again 35 in detail.

Having described my invention, I claim: 40 1. A piston ring comprising a pair of superimposed rings, both of said rings being split to permit expansion and contraction, and links secured at one end to one of said rings and at the other end to the other of 45 said rings, said links extending across the splits in said rings.

2. A piston ring comprising a pair of superimposed rings including an upper wearing ring and a lower control ring, both 50 of said rings having splits therein, said splits being arranged one above the other, a pair of links, one end of one of said links being secured to the wearing ring and the other end of said link being secured to the control 55 ring, said links extending across the splits in said rings.

3. A piston ring comprising a pair of superimposed rings including an upper wearing ring and a lower control ring each 60 of said rings having a split therein, said splits being arranged one above the other, said wearing ring having transverse notches in the lower face thereof, said notches being arranged one on either side of the split in 65 the ring, said control ring having notches

formed therein, said notches being arranged one on either side of the split in the control ring, a pair of links, upwardly and downwardly extending lugs one on either end of each of said links, said lugs fitting into 70 said grooves in the rings, one lug fitting into a groove in the wearing ring and the other lug fitting into a groove in the control ring and said links extending across the splits in the rings.

4. A piston ring comprising a pair of superimposed rings, both of said rings being split to permit expansion and contraction, and links secured at one end to one of said rings and at the other end to the other of 75 said rings, said links extending across the splits in said rings, and a downwardly extending shroud on said wearing ring, said shroud extending over and enclosing the wearing ring.

In testimony whereof, I affix my signature.

BERNARD YOUNG.
